BABY CRIB

Walter J. McNabb, Stockton, Calif., assignor of
one-half to William R. Cochrane

Application April 20, 1940, Serial No. 330,703

7 Claims.

(Cl. 5—11)

This invention relates generally to an improvement in nursery furniture, and particularly the invention is directed to an improved crib or baby bed.

In cribs of the type now commonly in use, the mattress frame—and consequently the mattress, etc.—is immovable vertically and by reason of this fact and the depth of the crib, a person attending a child must pick up the child from the crib and place the child on a higher table or the like, in order to conveniently change the child's clothing or otherwise administer thereto.

In order to avoid the necessity of so transferring the child, I propose, as the principal object of this invention, to construct a crib so that the bed or mattress frame is adjustable from a normal lowered position upward to a substantially raised position whereby when so raised, a person can easily and conveniently attend to the child without removing the child from its crib.

Another object of the invention is to provide a crib, as above, wherein the vertical movement of the mattress frame is accomplished through the medium of a foot pedal, thus leaving the person's hands free to steady the child, or adjust the bed covers during the movement of the mattress frame.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawings similar characters of reference indicate corresponding parts in the several views:

Figure 1 is a front elevation of the improved crib.

Figure 2 is a cross-section on line 2—2 of Fig. 1, the mattress frame being shown in a fully lowered position.

Figure 3 is a longitudinal sectional elevation on line 3—3 of Fig. 2, with the mattress frame lifted somewhat.

Figure 4 is a fragmentary longitudinal section on line 4—4 of Fig. 2.

Figure 5 is a fragmentary plan view of the foot pedal, shown in connection with its holding ratchet.

Referring now more particularly to the characters of reference on the drawings, the improved crib includes, as usual, cover posts 1 which form the legs of the crib; such posts being connected by side panels 2 and end panels 3 which extend from a plane somewhat below the bed level to the upper ends of said legs.

A mattress frame is disposed in the crib and is normally disposed at bed level; such mattress frame comprising a rigid border frame 4 of rec-

tangular configuration, and a resilient or spring sheet 5, preferably of metal and of mesh type, is carried by frame 4 and forms the mattress support. When in lowered or normal position, frame 5 rests on blocks or cross cleats 6 fixed on the end panels 3 adjacent but above the lower edges thereof.

At the ends and adjacent the corners, the frame 4 is provided with rigid ears 7 which project through vertical slots 8 in the corner posts 1, and thence extend into enlarged vertical grooves or pockets 9 in said posts; said slots and grooves being of sufficient length to allow of movement of the mattress from its lowered or normal position upward to a position adjacent the top of the crib.

The raising and lowering of the mattress frame is accomplished in the following manner:

A flexible cable 10 is connected at one end to each of the ears 7 within the corresponding groove 9, the cable extending upward over a pulley 11 in the upper end of said groove, and thence downward and about a pulley 12 in the lower end of said groove. From the corresponding pulley 12 each cable passes through an opening 13 in the corner post, and then extends longitudinally of the crib to substantially the middle thereof; the two opposed cables adjacent one side of the crib being secured in opposed winding relation on a drum 14 fixed on a horizontal, transverse shaft 15, while the two opposed cables adjacent the other side of the crib are secured in opposed winding relation on another drum 16 likewise fixed on said shaft 15.

It will thus be seen that upon rotation of shaft 15 in one direction, cables 10 will wind onto drums 14 and 16, causing the mattress frame to move upward relative to the remainder of the crib, while unwinding of the cables from the drum permits the mattress frame to lower of its own weight.

To manually rotate shaft 15, I provide a transverse lever 17 disposed below shaft 15 and pivoted at one end on one side 2 of the crib; such lever 17 extending from said pivot across the crib and projecting below the lower edge of the other side 2, a foot pedal 18 being mounted on the projecting end of said lever. This lever is normally raised and another flexible cable 19 is fixed at one end on the lever at a point remote from its pivot, and extends upward and winds about, and is fixed at its other end on, a third drum 20 on shaft 15. The cable 19 is so wound on drum 20 that upon depression of pedal 18 and downward swinging movement of lever 17, cable 19, as it runs off drum 20, rotates the latter in a direction to cause cables 10 to wind onto drums 14 and 16 and to raise the mattress frame.

Adjacent pedal 18, lever 17 rides in a vertical slot 21 in a suitably mounted arcuate guide plate

22; the portion of the plate along one side of slot 21 being formed as a ratchet 23 having downwardly facing teeth, the lever being adapted for holding engagement with any one of said teeth. A leaf spring 24 is fixed on lever 17 and rides against plate 22 on the opposite side of the slot from ratchet 23; such spring urging lever 17 laterally into engagement with said ratchet. Thus, as a person depresses pedal 18, the mattress frame is raised to the desired position, and when lever 17 is latched with ratchet 23, the mattress frame remains so raised. To lower said frame, the pedal is shifted laterally in a direction to release lever 17 from the ratchet, and the frame returns to a normal lowered position of its own weight, and at a speed controlled by foot pressure on the pedal.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention, what I claim as new and useful and desire to secure by Letters Patent is:

1. In a crib having side and end panels supported by corner posts, a separate rectangular mattress frame fitting between said side and end panels for relative vertical movement, rigid elements projecting from the ends of said frame adjacent the corners thereof, the corresponding corner posts having vertical slots opening into vertical pockets therein, said elements slidably engaging in said slots and projecting into the pockets, a pulley mounted in each pocket adjacent its upper end, another pulley mounted in each pocket adjacent its lower end, a flexible cable attached at one end to each element and thence extending upward and over the upper corresponding pulley and thence passing downward and about the lower corresponding pulley, said cables extending longitudinally of the crib toward its opposite end from said lower pulleys, and actuating means mounted on the crib and connected with the other ends of said cables for pulling said cables in a direction to raise said elements.

2. In a crib having side and end panels supported by corner posts, a separate rectangular mattress frame fitting between said side and end panels for relative vertical movement, rigid elements projecting from the ends of said frame adjacent the corners thereof, the corresponding corner posts having vertical slots opening into vertical pockets therein, said elements slidably engaging in said slots and projecting into the pockets, a pulley mounted in each pocket adjacent its upper end, another pulley mounted in each pocket adjacent its lower end, a flexible cable attached at one end to each element and thence extending upward and over the upper corresponding pulley and thence passing downward and about the lower corresponding pulley, said cables extending longitudinally of the crib toward its opposite end from said lower pulleys, a transverse shaft journaled below the mattress frame, drums fixed on said shaft, the other ends of the cables being fixed on said drums so as to wind said cables on the drums upon rotation of the shaft in one direction, and actuating means

connected with said shaft to rotate the shaft in said one direction.

3. A device as in claim 2 in which said actuating means comprises a vertically movable lever pivoted at one end on the crib below the mattress frame and said shaft, a foot pedal mounted on the other end of said lever, another drum fixed on the shaft, and another flexible cable connected at one end on said lever at a point remote from the lever pivot and connected at its other end on said other drum; said other cable normally being wound on said other drum and in a direction to rotate said shaft in said one direction upon downward vertical movement of the lever and resultant unwinding of said other cable from said other drum.

4. In a crib, a crib frame, a mattress frame, means mounting said mattress frame in connection with the crib frame for guided vertical movement, a shaft journaled on the crib frame below said mattress frame, means including flexible elements connected between the crib frame, the mattress frame and the shaft to raise said mattress frame upon rotation of the shaft in a direction to wind the flexible elements thereabout, a depressible foot pedal mounted on the crib frame, and means connected between said foot pedal and the shaft to rotate the latter in said direction upon depression of said pedal.

5. In a crib, a crib frame, a mattress frame, means mounting said mattress frame in connection with the crib frame for guided vertical movement, a shaft journaled on the crib frame below said mattress frame, means including drums mounted on said shaft and flexible elements connected at one end on said drums and at the other end on said mattress frame above the shaft, means on the crib frame guiding the elements so as to cause the portion of the elements above the mattress frame to be pulled up upon rotation of said shaft in a direction to wind said flexible elements on the drums, actuating means mounted on the crib frame and means between the actuating means and the shaft operative to rotate the shaft and drums in said direction.

6. A device as in claim 5 in which said actuating means includes a depressible foot pedal, another drum on the shaft above said pedal and another flexible element connected at one end on and normally wound about said other drum, the other end of said other flexible element being connected with the foot pedal.

7. In a crib, a crib frame, a mattress frame, means mounting said mattress frame in connection with the crib frame for guided vertical movement, a shaft journaled on the crib frame below said mattress frame, means including drums mounted on said shaft and flexible elements connected at one end on said drums and at the other end on said mattress frame above the shaft, means on the crib frame guiding the elements so as to cause the portion of the elements above the mattress frame to be pulled up upon rotation of said shaft in a direction to wind said flexible elements on the drums, another drum mounted on said shaft, another flexible element connected at one end on said other drum and normally wound thereabout, a lever pivoted on the crib frame for vertical swinging movement below and away from said shaft, the other end of said other flexible element being connected with said lever at a point thereon relative to the pivot of the lever so as to be pulled upon depression of the lever, and a foot pedal mounted on said lever to swing the latter.

WALTER J. McNABB.
